UNITED STATES PATENT OFFICE.

EDMOND M. WATKINS, OF TRENTON, NEW JERSEY.

FASTENER.

1,398,288.

Specification of Letters Patent. Patented Nov. 29, 1921.

Application filed November 21, 1919. Serial No. 339,596.

To all whom it may concern:

Be it known that I, EDMOND M. WATKINS, a citizen of the United States, residing at Trenton, in the county of Mercer and State 5 of New Jersey, have invented new and useful Improvements in Fasteners, of which the following is a specification.

This invention relates to clasps or fasteners and more particularly to that type of 10 these devices which is adapted for use in this connection with garters or other articles of apparel and has as its object the provision of a fastener which is simple and durable in construction, which is so constructed to insure the wearer against accidental opening of the clamping members and which by reason of its simplicity of 15 structure may be economically manufactured. A further object of the invention is 20 the provision of a fastener which is readily operable and may be quickly engaged and disengaged from a garment and by reason of its construction will not tear or pull the threads of the garment it engages.

25 Articles of this type are well known in the art and it is the object of my invention to improve upon these, more particularly in the means for holding the clamping members in apparel engaging position. My device 30 consists broadly of two jaws hingedly connected and provided with a stud and socket coöperating therewith to hold the jaws in closed position.

In the accompanying drawings, I have 35 shown several forms which my invention may take, but it should be understood that such variations may be made in these embodiments of my invention as come within the scope of the claims appended to this 40 specification. In these drawings:—

Figure 1 is a plan view showing the fastener opened up.

Figure 2 is an edge elevational view.

Figure 3 is a longitudinal cross-sectional 45 view.

Figure 4 is a view showing the jaw provided with the socket member with the top of the housing removed disclosing a modified form of stud retaining structure.

50 Figure 5 is a view of the blank from which the jaw provided with the socket member is formed.

Figure 6 is a fragmentary view showing a modified form of socket structure, the top 55 wall of the housing being removed.

Figure 7 is a view similar to Figure 6

showing a still further modified form of socket structure, and

Figure 8 is a fragmentary view of the socket member shown in Figure 1 with the 60 top wall of the housing removed.

Referring to the drawings more in detail, 10 indicates a loop to which are hinged two jaws 1 and 2, both being provided at their ends with enlargements 3 having attached 65 thereto serrated garment or apparel engaging pads 4.

As will be observed, the jaws are hingedly secured to the loop 10 by means of fingers which are turned about the loop, the jaw 2 70 being provided with a single finger 5 and the jaw 1 with two spaced fingers 6 and 7 for this purpose. Between the fingers 6 and 7 is formed a short spring finger 8 which, as will be observed from Figures 2 and 3, is 75 bent inwardly and serves to normally maintain the two jaws in the separated position shown in Figure 2.

In order to retain the jaws in closed and operative position, the jaw 2 is provided 80 with a stud 9 which serves to coöperate with a socket member comprising a housing 11 formed integral with the jaw 1. The two jaws may be made from any suitable material and in the present instance are shown 85 as spring metal, the jaws being died out to the form indicated.

Referring more particularly to the jaw 1, it will be observed that intermediate its ends 90 it is provided with laterally extending wings 12, 13, adapted to be bent over to the position shown in Figure 1 to form the housing 11 of the socket member.

Referring now to Figures 5 and 8, the 95 socket member comprises two openings 14 and 15, the latter being formed by two meeting semi-circular recesses 16, 17, in the abutting edges of the wings 12 and 13. Through the latter opening is adapted to project the stud 9 to be engaged by suitable stud retaining means which in the present instance is shown as comprising two arms 19 pivoted about a common fulcrum in the form of a pintle 20, seated in the opening 20' in the jaw. The arms are shown as being provided 100 with end loops or fingers 21 which engage the stud projecting through the opening 15 and are held in stud engaging position by means of a spring 22 shown in this form of 105 my device as being in the shape of a split ring 22, the meeting ends of which engage each of the fingers at the points where they

join the body of the retaining arms. The retaining arms 19 are held in a position in which the fingers 21, 22, are slightly spaced apart so as to permit the wedging of the 5 stud 9 therebetween by means of shoulders 40 upon the releaser arms 23, which shoulders engage the fastener housing adjacent the opening 24, and thus limit the pivotal movement of the retaining arms. In order 10 to permit the releasing of the stud from the grasp of the retaining arms, I provide stud releasers 23 projecting through openings 24 in the socket member housing, and while I have shown these releasers as being formed 15 integral with the retaining arms it should be understood that the construction might be readily modified by having the releasers as separate members.

When the jaws are closed it is not necessary to press the stud releasers 23, as the 20 retaining arms are pressed apart when the stud 9 is wedged between their fingers 21, but in order to open the jaws and in order to guard against accidental disengagement of 25 the stud and its socket, I have so constructed my fastener that it is necessary to press the releasers 23.

In Figure 4 the modified form of socket member is substantially similar to that 30 shown in Figure 8 and comprises the stud retaining arms 19', but I have shown a modification in the means for holding the arms in stud engaging position, the means in the present instance comprising two curved 35 springs 25 whose ends lie against the side walls of the housing and raised center portions abut the fingers of the retaining arms.

The modification of the socket shown in Figure 6, I have found to be sometimes desirable, and it comprises a short stud or pintle 26 about which is looped a wire spring having two substantially parallel portions 27 adapted to form retaining arms for the stud and being bent at points 28 laterally 45 in opposite directions to project through openings 29 in the housing. The parallel portions 27 are held in the slightly spaced relation shown in Figure 6 so that the stud 9 may be wedged therebetween by means of a 50 tongue 42 struck up from the jaw 1 adjacent the opening 14. At points 30, the spring is bent so as to form two parallel portions which at the other ends of the openings 29 are bent inwardly into the casing. In this 55 manner I form from a single piece of wire, stud retaining arms and releasers which in operation are very effective.

The modification shown in Figure 7 resembles somewhat the preferred form shown in 60 Figure 8, but it is to be observed that in Figure 8 while the arms are pivoted in the same plane in Figure 7 they are pivoted one above the other about a common fulcrum 32.

Each of these arms 33 is provided with curved 65 stud engaging fingers 34 and with oppositely extending stud releasers 35 projecting through the usual openings in the housing. The arms are urged by means of a spring 36 to engage the stud and are not permitted to come to entirely closed position and thus 70 prevent the wedging of the stud between their fingers, by shoulders 37 which engage the interior of the housing adjacent the releaser openings.

From a casual reading of the above specification, it will be observed that by the construction described in which I have shown several embodiments of my invention, there is provided an unusually effective fastener which is not liable to be unintentionally or 80 accidentally opened and which by reason of its extremely simple structure is entirely durable and economical to manufacture.

What I claim is:

1. A fastener comprising jaws hingedly 85 connected, one of said jaws having a stud and the other of said jaws being provided with a socket member, said socket member comprising a housing, pivoted stud retaining arms in said housing, a pintle in the housing 90 serving as a common fulcrum for said arms, and stud releasers extending from said housing.

2. A fastener comprising a pair of jaws hingedly connected, a stud on one of said 95 jaws, an integral housing on the other of said jaws having an opening therein for said stud, pivotally movable stud engaging arms in said housing, a common fulcrum for said arms, and stud releasing means integral 100 with said arms extending from the housing.

3. A fastener comprising a pair of jaws hingedly connected, a stud on one of said jaws, an integral housing on the other of 105 said jaws having an opening therein for said stud, pivotally movable stud engaging arms in said housing, a common fulcrum for said arms, a spring in the form of a split ring holding said arms in stud grasping position, and stud releasing means integral with said 110 arms extending from the housing.

4. A fastener comprising a pair of jaws hingedly connected, a stud on one of said jaws, the other of said jaws having a body portion, lateral extensions on said body portion bent upwardly and over said body portion to form an integral housing, said housing having an opening therein for said stud, pivotally movable stud engaging arms in 115 said housing, a common fulcrum for said arms, and stud releasing means integral with said arms extending from the housing.

In testimony whereof I have hereunto set my hand.

EDMOND M. WATKINS.
